(57) **CLAIM**

The ornamental design for an umbrella frame, as shown and described.

DESCRIPTION

FIG. 1 is a perspective view of an umbrella frame showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an exploded view of the umbrella frame thereof; and,

FIG. 9 is an enlarged view of the selected portion 9 in FIG. 1.

The broken lines shown in the drawings depict portions of the umbrella frame that form no part of the claimed design.
